UNITED STATES PATENT OFFICE

104,221

DESIGN FOR A COMBINED FLOWER POT AND STAND OR SIMILAR ARTICLE

Jacob S. Miller and Joe Tyson, Washington, D. C.

Application December 23, 1936, Serial No. 66,716

Term of patent 14 years

To all whom it may concern:

Be it known that we, Jacob S. Miller and Joe Tyson, citizens of the United States, residing at Washington, in the District of Columbia, have invented a new, original, and ornamental Design for a Combined Flowerpot and Stand or Similar Article, of which the following is a specification, reference being had to the accompanying drawing, forming part thereof.

The figure is a perspective view of a combined flowerpot and stand, showing our new design.

We claim:

The ornamental design for a combined flowerpot and stand or similar article, as shown.

JACOB S. MILLER.
JOE TYSON.
